(No Model.)

W. B. RUST.
PRINTING ATTACHMENT FOR ROLL PAPER HOLDERS.

No. 579,549.

Patented Mar. 23, 1897.

UNITED STATES PATENT OFFICE.

WILLIAM B. RUST, OF PORTLAND, OREGON.

PRINTING ATTACHMENT FOR ROLL-PAPER HOLDERS.

SPECIFICATION forming part of Letters Patent No. 579,549, dated March 23, 1897.

Application filed December 29, 1896. Serial No. 617,387. (No model.)

To all whom it may concern:

Be it known that I, WILLIAM B. RUST, a citizen of the United States, and a resident of Portland, county of Multnomah, State of Oregon, have invented a new and useful Improvement in Printing Attachments for Roll-Paper Holders, of which the following is a specification, reference being had to the accompanying drawings as constituting a part hereof.

10 My invention relates to devices designed to print on the wrapping-paper wound on the well-known rotary holders; and the object of my invention is to introduce certain improvements for the purpose of perfecting such device, as will be apparent from the description of my invention herein given.

Figure 1 in the drawings is a vertical section taken through the center of my invention. Fig. 2 is an end elevation thereof. Fig. 3 is a partial elevation taken from the back of my invention with parts broken away, so as to disclose as much of the construction thereof as possible. Fig. 4 is a perspective of a detail, and Fig. 5 is likewise a detail.

25 The numbers designate the parts referred to. My invention is mounted on two horizontal slats 1 1^a, arranged oppositely and to be secured on the table on which my invention is to be placed by means of ordinary wood or 30 thumb screws 2 3, as shown. The slats 1 are respectively provided with the horizontal slots 4 and the slanting slots 5, 6, and 7.

The printing mechanism is contained in the case 8, which is mounted on said slats 1 1^a by 35 means of the wire frame 9, the members of said frame 9^a 9^b having at their ends eyes 9^c, through which are inserted the ends of the rod 10, extending between and through the slots 4 of the slats 1 1^a, the ends of the rod 10 40 being provided with a screw or other device adapted to prevent the same from being pulled out of such slots 4.

The coils 11 around the end of the rod 12 form a hinge, and the upwardly-projecting part of 45 the frame 9 extends around the front of the case 8 and is affixed thereto by crimping the edges of the case over the wire and fixing the parts so united by soldering.

The rod 12 may be shifted laterally from one 50 to either of the other slots 5 6 7 to adjust the printing-roll to the face of the wrapping-paper as the diameter of the latter diminishes

by consumption. The ends 9^a and 9^b, as is apparent, slide with the rod 10 in adjusting the position of the rod 12.

55

The printing-roll 13, bearing against the face of the paper roll P, the inking-rolls 14 15, and the blotting-roll 16 are arranged in the case 8 and coöperate together, as shown in Fig. 1. The bearings for the rolls 13 and 16 60 are fixed.

The inking-rolls 14 and 15 are journaled in slotted bearings 17 and 18, (see Fig. 2,) so that by means of the coil-spring 19 they will automatically adjust themselves to the surface of 65 the printing-roll, said slotted bearings giving to the inking-rolls some play to allow for any unevenness of the surface of the printing-roll.

The inking-rolls (see Fig. 5) have a covering of some ink-retaining material and are respectively provided with the longitudinal slots 20 70 21 22 23, filled with some absorbent material for retaining an additional supply of ink, to be diffused to the surface-covering of such rolls as the ink on the latter is used up, and 75 the vertical peripheral slots 24 25, with which the inking-rolls are respectively provided, are designed to receive and hold any ink drainage from the surface of such rolls. The roll 16 is also covered with some absorbent material 80 and is interposed between the upper inking-roll and paper surface to assist in evenly distributing and removing any superfluous ink on the face of the printing-roll.

My invention is applied to the paper-holder 85 in the usual way, being fixed between the standards of the latter, and the frame 9 is made of spring-wire and adapted to press the printing-roll against the paper roll.

Now what I claim is—

1. In a roll-paper-printing attachment in combination the frame 9 and connecting-rods 10, 12, mounted upon a suitable support adapted to be affixed to a table or other surface, and to admit of the frame being laterally 95 shifted thereon to adjust the device to the face of the paper roll, the case 8 and the printing mechanism mounted therein and comprising the printing-roll 13 the inking-rolls 14 15, and the blotting-roll 16, the bearings for the 100 rolls, 13, 16, being fixed and the rolls 14 and 15 being journaled in slotted bearings, and adapted to bear against the surface of said printing-roll, substantially as described.

2. In a roll-paper-printing attachment in combination the frame 9 and connecting-rods 10 12, mounted upon the slats 1, and 1³, the case 8 containing the rolls 13 14 15 16, the 5 slotted bearings 17, 18, for the rolls 14 15, and the springs 19 for the purpose specified, the inking-rolls, 14, 15, having longitudinal and peripheral slots 20, to 23, and 24, 25, the for-

mer containing some absorbent material, substantially as set forth.

In witness whereof I have hereunto affixed my signature in the presence of two witnesses.

WILLIAM B. RUST.

Witnesses:

GEO. W. HAZEN,
T. J. GEISLER.
